LOUIS STEINBERGER, OF BROOKLYN, NEW YORK.

DISK STRAIN-INSULATOR.

1,212,704.

Specification of Letters Patent. Patented Jan. 16, 1917.

Application filed December 31, 1912. Serial No. 739,485.

To all whom it may concern:

Be it known that I, LOUIS STEINBERGER, residing at Brooklyn, in the county of Kings and State of New York, have invented certain new and useful Improvements in Disk Strain-Insulators, of which the following is a specification.

This invention relates to strain insulators and particularly to those of the disk type.

It is a well known principle in this type of insulator, as shown for instance in a patent issued to me November 27th, 1908, numbered 904,370, to form the surface of the disk with annular corrugations or flanges for serving the double purpose of shedding rain water and of increasing the resistance to creepage around the surface of the disk from one strain member to the other by providing a greater surface extent. Numerous forms of flanges, hoods, corrugations and such irregularities of surface have been provided on the disks and on the body parts of insulators for effecting this result, but heretofore all of such constructions have necessitated the addition of material to the structure for forming the flanges, corrugations, etc., and have therefore resulted in an increase in cost and weight of the structure. In all instances the disk has been provided as a positive element and the ridges, corrugations, etc., have been added to the disk substantially as separate elements.

The particular object of the present invention is to provide an insulator of the class referred to wherein the irregularities of surface for providing water sheds and otherwise increasing the insulating value of the disk, without increasing the size of the disk, are obtained in what might be called a combination of the disk and the irregularities, to the end that the disk, as a positive element, is not present independently of the corrugations or ridges, nor are the ridges, as separate elements, present independently of the disk. The two are combined so that in forming the ridges, a disk is produced substantially without the addition of material to the structure for providing either of the features independently of the other. A further object is to provide a structure as above which is simple of design, which embodies a minimum of material, and which is therefore cheap to manufacture, but which is nevertheless thoroughly efficient and embodies maximum efficiency and minimum material, both as to its insulating

qualities and as to its mechanical strength, for a given sized disk.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention: Figure 1 is a transverse sectional view through an insulator embodying the features of this invention, Fig. 2 is a plan view of the same partly broken away for the saving of space, and Fig. 3 is a modification.

Referring to the drawings for a more detailed description of the structure illustrated, and referring particularly to Figs. 1 and 2, the numeral 1 indicates the body portion of the insulator, which portion is preferably of a more or less elongated cylindrical shape for receiving the strain members illustrated as 2 and 3.

The strain members illustrated each comprise a short bolt having an eye as 4 at its outer end and having its inner end formed with a head 5 embedded in the material of the body 1. The inner ends of the two strain members are spaced apart and the material of the body fills the intervening space for effectually insulating the members from each other.

It will be understood that, though I have shown and described the strain members as comprising simple bolts having heads spaced apart and molded within the body 1 in axial alinement, said strain members may of course take any form desired for increasing the mechanical strength of the structure in resisting strains placed upon the strain members.

The disk portion of the structure is illustrated generally by the reference numeral 6, and comprises a wall or annular flange of substantially uniform thickness springing from the body 1 between the ends of the body, said flange or wall being bent concentrically of the body so as to present a serpentine aspect when viewed in cross-section. As shown in the drawings, Fig. 1, this wall or flange is illustrated as springing from a

plane at substantially the median transverse line of the body, in an upward direction as at 7, for a short distance, turning thence downwardly into a leg 8, thence upward into leg 9, thence downwardly into leg 10, upwardly into leg 11, downwardly into leg 12 and upwardly into leg 13. The bend of the leg 7 into the leg 8 forms an annular ridge 14 projecting upwardly, said legs likewise form 10 an annular depression 15 at the under side of the disk. The bend of the leg 8 into the leg 9 forms an annular ridge 16 projecting downwardly and said legs also form an annular groove or recess 17 on the upper surface 15 of the structure. Similar ridges and grooves are formed by the legs 9—10, 10—11, 11—12 and 12—13.

It is apparent that the structure shown and described provides ridges and depressions, with all the advantages thereof but without material increase in the quantity of material used, for a given sized disk. The ridges on one side of the disk accommodate the depressions of the other side.

25 The thickness of the material forming the wall or flange 6 may preferably be only sufficient to lend efficiency against puncturing and for lending the required mechanical strength. In this connection it should be 30 noted that a disk constructed with concentric annular grooves and ridges, the ridges of one side being opposite the grooves of the other side, and rendering the serpentine cross-section shown, is of considerably 35 greater mechanical strength than a disk of the same diameter, which contains the same amount of material, would be, if made flat. Likewise if some of such material should be subtracted from the flat disk and molded up 40 to form annular ridges or corrugations on the otherwise flat surface, the taking away of that material would only reduce the strength of the disk that much. The structure shown therefore is seen to have considerably 45 greater mechanical strength than a flat disk of the same amount of material, either with or without ridges on the disk.

In order to further strengthen the structure illustrated, and to more effectually 50 guard against puncture it may be desirable to increase the thickness of the wall or flange 6 in the vicinity of the body. The flange may be made thickest adjacent the body and be of gradually decreasing thickness toward the edge, or may be otherwise 55 reinforced, as desired. Here it may be noted that wherever, in this specification and claims, the term "substantially of uniform thickness" or its equivalent, is employed, such term is intended to include such variations in thickness as may be desirable for 60 lending required strength and resistance to puncturing to given parts as above described.

65 In Fig. 1, the leg 8, nearest the body 1, is

longest, and the legs 9, 10, 11 and 12 are successively shorter so that a line drawn radially across the upper surface of the disk from the body 1 to the edge thereof, touching the several ridges will converge with 70 a similar line drawn along the bottom surface of the disk, at a point slightly beyond the edge. Such an arrangement has advantages, such as giving a maximum increase in surface extent nearest the body 1, and 75 such as giving greater mechanical strength to the structure, etc. This arrangement however, is not essential to the principles of this invention, for obviously the parts could be arranged in any other desired manner. 80 One such other arrangement is illustrated in Fig. 3, wherein the ridge 18 and depression 19 nearest the body are the less marked, and those therebeyond are of successively 85 increasing extent.

In Fig. 3, is illustrated a construction wherein the outermost leg as 20, of the flange, is relatively long and is well adapted to form one side of a water shedding groove as 21 encircling the flange. The other side 90 of the groove is formed by a projecting portion 22 springing from the outer surface of the leg 20. Water entering this groove will flow to the lowest point and fall off without reaching either surface of the disk.

It is apparent that, in both of the structures illustrated, the depressions or grooves between the ridges serve to present relatively dry areas even in the presence of heavy rain. At least one side of the structure will necessarily be almost entirely dry.

95 As many changes could be made in this construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent, is:—

1. An insulator comprising a body, an annular flange formed on said body, the material of said flange being formed with bends concentrically of the body to provide 115 a plurality of ridges and depressions on the opposite surfaces of said flange concentrically of the body, the ridges on one surface being disposed opposite the depressions on the other surface, the ridges being formed relatively higher toward the periphery of the flange than near the body, the outer annular surface of the outermost ridge being inclined from its lower annular edge upwardly and inwardly toward the body in 125 substantial frusto-conical shape, and an annular flange formed on said relatively inclined surface intermediate the height thereof, being inclined oppositely to the inclination of the outer surface of said ridge 130

to provide an annular V-shaped groove on the inclined outer surface of said outermost ridge.

2. In a disk type insulator, the combination with a centrally disposed body portion of insulating material having attaching means thereon, of an annular flange bent substantially concentrically of the body into serpentine cross section forming a series of 10 annular ridges and depressions at opposite sides thereof, and the material of the flange being of gradually decreasing thickness away from the body portion, and said flange being connected to the body intermediate 15 the planes of the ends of the body, substantially as shown and described.

3. In a disk type insulator, the combination with a centrally disposed body portion of insulating material having attaching 20 means thereon, of an annular flange bent

substantially concentrically of the body into serpentine cross section forming a series of annular ridges and depressions at opposite sides thereof, said flange being connected to the body at a plane substantially midway between the opposite ends of the body, the first bend of the flange being toward the plane of one end of the body, the next bend being toward the opposite end of the body, the third bend being toward the first end of the body, and so on to the periphery of the flange, and all of said bends terminating short of the planes of the ends of the body. 25 30

In testimony whereof I affix my signature in the presence of two witnesses.

LOUIS STEINBERGER.
